ATTORNEY.

UNITED STATES PATENT OFFICE

ANNA M. FISHER, OF LOS ANGELES, CALIFORNIA

MESSAGE HOLDER

Application filed September 16, 1929. Serial No. 393,107.

This invention relates to a cake ornament support intended for use upon various kinds of cakes and which is intended to be employed at birthday parties and various other occasions of social gatherings.

An object of the invention is to provide an ornament support adapted for being mounted upon the cake and which will be suited to supplant the candles which it is, at present customary to mount upon birthday cakes using a number of candles equal to the number of years of the person's age whose birthday is being celebrated. By this invention a pleasing substitute for such candles is provided, a number of small attractive ornaments being instead supported upon the cake and the minds of the guests being thus diverted from the practice (sometimes embarrassing to the hostess or guest of honor) of counting the candles to ascertain the age of the person whose birthday is being celebrated.

Among the social occasions when it is customary to serve cakes and for which my newly invented ornament support is suitable are: weddings, card parties, stag parties, christenings, anniversary parties, and holiday occasions; also on special advertising occasions.

With the foregoing and other objects and advantages in view, as will hereinafter appear, the invention comprises an ornament support having a railing which is adapted to be supported upon a cake in spaced relation to the top surface thereof, and which includes a master object within said railing and a plurality of subordinate related objects supported by said railing. The master object will usually be of an ornamental character and the subordinate objects will ordinarily be cards, miniature toys, or other small articles suitable to be presented to the guests as souvenirs.

Referring to the accompanying drawing, which illustrates a preferred embodiment of the invention, upon a plate or platter 3 is shown a cake 4, in the present instance a rather large circular cake such as would be considered suitable for a birthday party. This cake has a substantially flat top surface

5, a fragment of which is broken away at 6 to show more clearly the frosting 7 with which the cake is covered.

Referring now to the ornament support, in the illustrated embodiment thereof, the 55 rectangular base plate 8 carries a circular railing 9 which is supported above said base plate in vertically spaced relation thereto by means of the posts or upright arms 10. Within said railing 9 is the master object 11 60 which, in the present instance, is a doll mounted upon wire posts 12 the lower ends of which are secured to the central portion of the base plate 8.

From the railing 9 are suspended a plurality of subordinate objects 15, these objects in the present instance being miniature dolls which are suspended from the railing by means of hooks 16, each of said dolls carrying a small paper roll 17 upon which is inscribed some suitable message, slogan or motto. These miniature dolls are intended for distribution among the guests and the matter inscribed upon the rolls 17 conveys the desired messages to the guests. 75

As has already been stated, the master object need not be a doll but may be a flag, flower, candle, or other attractive object, and the miniature dolls 15 may be exchanged for miniature pipes, cards, lanterns, caps, valentines, etc.

The base plate 8 may be made of thin wood and may be slightly embedded in the frosting 5 before the frosting has hardened. As an additional means for stabilizing said base plate upon the cake, pins 20 are provided which project downwardly from the base plate into the plate. 85

The tag 21 is attached to an object such as a horn 22 carried by the master object 11, said tag having thereon any suitable advertising or other subject matter corresponding to the message 17. 90

Claims—

1. In a cake ornament support, a railing, means to support said railing upon a cake in a spaced relation to the top surface thereof, a master object within said railing, and subordinate related objects supported by said railing. 100

2. In a cake ornament support, a wire railing, legs to support said railing upon a cake in a spaced relation to the top surface thereof, a master object within said railing, and subordinate related objects supported by said railing.
3. In a cake ornament support, a platform adapted to rest upon a cake, a master object mounted upon said platform, a railing surrounding said master object, means mounted upon said platform to support said railing, and subordinate objects related to said master object and supported by said railing.

In testimony whereof I affix my signature.
